UNITED STATES PATENT OFFICE

CLIFFORD I. ENOCHS, OF ARDMORE, PENNSYLVANIA

DESIGN FOR A MEMORIAL STONE FOR GRAVES

Application filed September 2, 1930. Serial No. 36,850. Term of patent 14 years.

To all whom it may concern:

Be it known that CLIFFORD I. ENOCHS, a citizen of the United States, residing at Ardmore, in the county of Montgomery and the State of Pennsylvania, has invented a new, original, and ornamental Design for a Memorial Stone for Graves, of which the following is a specification, reference being had to the accompanying drawing, forming a part thereof.

The figure of the drawing is a perspective view of a memorial stone for graves showing the new design.

The broad design is the general aspect of the memorial stone, that is the base slabs on which doweled and cemented is the upright slab, with the base slabs projecting forwardly beyond the upright slab, which forms a background or back setting for the tubes doweled and cemented on the end base slabs and the vase doweled and cemented on the centre base slab.

What is claimed is:

The ornamental design for a memorial stone for graves as shown and described.

CLIFFORD I. ENOCHS.
